UNITED STATES PATENT OFFICE.

JOSEPH KUGLER, OF WACONIA, MINNESOTA.

SURGICAL APPLIANCE.

No. 801,385.

Specification of Letters Patent.

Patented Oct. 10, 1905.

Application filed May 11, 1905. Serial No. 259,890.

To all whom it may concern:

Be it known that I, JOSEPH KUGLER, a citizen of the United States, residing at Waconia, in the county of Carver and State of Minnesota, have invented certain new and useful Improvements in Surgical Appliances, of which the following is a specification, reference being had therein to the accompanying drawings.

10 My invention relates to surgical appliances or bandages, and more particularly to that class of bandages used in controlling the lower limbs of persons addicted to "toeing in" or walking in what is known in common parlance as "pigeon-toed," one of the objects of said invention being to provide a device of the character described that shall be simple and inexpensive in construction, durable, effective in operation, and easy of adjustment.

20 Other objects and advantages of my invention, as well as the structural features by means of which these objects are attained, will be made clear by an examination of the specification, taken in connection with the accompanying drawings, in which the same reference-numerals indicate corresponding portions throughout, and in which—

Figure 1 is a perspective view of a lower limb, showing my improved device attached 30 and in operative position; and Fig. 2 is a perspective view of said device detached.

1 designates a strap, which may be made of any suitable material—elastic or inelastic, as desired. 2 designates a buckle secured to one 35 end of said strap, which is provided with holes 3 in its other end, by means of which the strap may be adjustably and removably secured in the vicinity of the knee to one of the limbs of the person upon which my said 40 device is used, as shown in Fig. 1. Removably and adjustably secured to said strap by a buckle 5 or by any other suitable means is a spiral or helical spring 6, which is secured

at its lower end to a strap 7, said strap being similar to strap 1, with the exception that it 45 is somewhat shorter and is provided with a buckle 8 at one end and holes 9 at the other end, so that said strap may be adjustably and removably secured to the leg in the vicinity of the ankle.

50 In operation the upper strap 1 is buckled around the limb near the knee, and the spiral or helical spring 6 is then wound spirally around the limb and as tightly as may be necessary, and the lower strap 7 is then buckled 55 around the limb at or near the ankle. The upper strap 1 is so adjusted that the end of the spring secured thereto is either on the outside or the back of the limb, and the lower strap is so adjusted that the end of the spring 60 is either on the outside or the front of the limb, so that the tension of the spring on the lower strap tends to turn the foot outward.

Having thus described my said invention, what I claim as new, and desire to secure by 65 Letters Patent of the United States, is—

In a device of the character described, a strap, a buckle carried thereby and by means of which said strap is adjusted and held in position, a second strap corresponding to the 70 first-mentioned strap, a laterally-projecting strap secured to each of the above-mentioned straps, a buckle carried by each laterally-projecting strap, a coil-spring adapted to be wound around the limb, and a tongue carried by each 75 end of the coil-spring and adapted to engage one of the buckles carried by the laterally-projecting straps whereby the spring may be adjusted and its tension loosened or tightened.

In testimony whereof I hereunto affix my 80 signature in presence of two witnesses.

JOSEPH KUGLER.
